PACKAGING DISH FOR CANDY OR THE LIKE

Marten Gottsegen, 1212 Lake Shore Drive,
Chicago, Ill. 60610

Filed Mar. 18, 1974, Ser. No. 451,848

Term of patent 14 years

Int. Cl. D9—03

U.S. Cl. D9—199

Fig. 1

Fig. 2

Fig. 4

Fig. 5

Fig. 3

FIG. 1 is a front perspective view of a packaging dish for candy or the like showing my new design;

FIG. 2 is a front elevational view thereof;

FIG. 3 is a top plan view thereof;

FIG. 4 is a rear elevational view thereof; and

FIG. 5 is a side elevational view thereof.

The broken line showing of the candy and wrapper in FIG. 1 is for illustrative purposes only.

I claim:

The ornamental design for a packaging dish for candy or the like, as shown and described.
